ATTORNEY

UNITED STATES PATENT OFFICE.

WILLIAM WHIITE, OF RUTHERFORD, NEW JERSEY, ASSIGNOR TO CLARENCE WHITMAN & CO., OF NEW YORK, N. Y.

DESIGN FOR A BEDSPREAD.

SPECIFICATION forming part of Design No. 29,257, dated August 23, 1898.

Application filed May 7, 1898. Serial No. 680,068. Term of patent 7 years.

To all whom it may concern:

Be it known that I, WILLIAM WHITE, a citizen of the United States, residing at Rutherford, Bergen county, New Jersey, have invented and produced a new and original Design for a Bedspread, of which the following is a specification, wherein reference is made to the accompanying drawing, in which the figure represents a bedspread embodying my design.

One half of the drawing is shown in detail, while the remaining portion, which is merely a "repeat" of the pattern, is represented in outline.

The characteristic features of my design are essentially those represented in the accompanying drawing.

The border B is made up of a block-like pattern comprising the rectangular figures a b. Within this border is an inner border 20 or pattern C, which is made up of a series of ornamental polygonal figures c, within which are ornamental circular figures d. Adjacent to the border C is a series of overlapping ornamental rings e, the field for which is formed 25 by a series of ornamental rectangular and circular figures f g, respectively.

What I claim is—

The design for a bedspread, substantially as shown and described.

WILLIAM WHIITE.
